Application October 25, 1947, Serial No. 782,091

11 Claims. (Cl. 200—52)

1

This invention relates to switches, and is particularly concerned with switches known as coin-operated switches. These switches are commonly used in vending machines or other mechanisms which are set in operation through a coin introduced therein.

In order that the switch may operate unfailingly, it must be designed to be operable under all conditions of humidity, heat, cold, vibration, and shock.

While a vending machine is ordinarily designed to operate with nickels, dimes, or quarters, nevertheless, a suitable switch must also be capable of operation by a so-called thin dime, that is, one which has been worn to such an extent that its weight will be approximately half the weight of a normal dime. Accordingly, one of the objects of the invention is to provide a switch mechanism operable by small weights which vary over a considerable range.

In the trade it is considered that for a switch of this type to be fully satisfactory, it must be capable of at least a million operations. Therefore, the switch must not have a switch blade in which there are highly stressed areas which are known to be subject to rapid fatigue under repeated operation pressures at the sensitive areas. The switch blade should be relatively unstressed and movable only through annular positions well within its elastic limit.

Accordingly, another object of this invention is the provision of a switch in which the internal forces are small and the mechanism simple, and in which no part has been excessively stressed, although having the desired operating characteristics. The present invention further contemplates a switch which is small and compact so that it may be positioned within a minimum space, and which by virtue of the close fit of all parts entering the cavity through the housing will substantially preclude the entrance therein of extraneous material as, for example, dust and moisture and which will be shockproof, vibration-proof, resistant to heat and cold, and of exceptionally long life.

The switch in the present application is shown as an independent unit without any related mechanism, which may vary depending upon the type of machine with which the switch is used.

A particular feature of the invention is the arrangement whereby adequate leverage is obtained to move positively the switch contacts, and at the same time there is provided means for overtravel of the operating lever to eliminate the possibility of damage to the switch contacts.

2

It is a further object of the invention to provide spring mechanism mounted within the housing for providing quick return of the operating lever to normal position after the coin force has been removed therefrom. The construction is such that even though the externally applied coin force produces a relatively large force within the housing as compared with the spring forces within the housing, nevertheless, the internal spring forces will be adequate to return the switch to normal position promptly upon the removal of the coin force.

These and other advantages of the invention will be more apparent as the description proceeds with the aid of the accompanying drawings, in which

Fig. 1 is a side elevation of the switch, showing the contacts extending therebelow and the operating lever extending to the left.

Fig. 2 is an end elevation of Fig. 1, looking from the right.

Fig. 3 is a view looking upwardly from the bottom of Fig. 1, with the housing broken away in part to show the means for securing the housing parts together.

Fig. 4 is an enlarged sectional elevation on the line 4—4 of Fig. 2, showing the switch parts in normal position.

Fig. 5 is a sectional elevation similar to Fig. 4, with the position of the contacts shifted, due to coin operation.

Fig. 6 is a sectional elevation similar to Figs. 4 and 5, showing the extent of over-travel that can occur without further change in the position of the contacts.

Fig. 7 is an enlarged vertical section on the line 7—7 of Fig. 5.

Fig. 8 is a vertical elevational view partly in section on the line 8—8 of Figs. 2 and 7.

Fig. 9 is a view corresponding to Fig. 4, showing a modification of the invention.

Fig. 10 is a section on the line 10—10 of Fig. 9.

Fig. 11 is a view from the reverse side of Fig. 9 broken away in part showing the manner of connecting the hair spring to the shaft.

The invention consists basically of a housing, two fixed spaced contacts, an intermediate movable contact, and a lever for moving the intermediate contact from a normal position against one fixed contact to a second position against the other fixed contact, all combined with means that permits the operating lever to continue arcuate movement after the second contact has been made without further movement of the contacts.

Referring to the relatively large scale draw-

ings, Figs. 1, 2 and 3, the housing is shown to be comprised of opposed cover plates 2 and 4, and a suitably cored center body portion 6. These three parts are held together by tubular rivets 8 that pass through aligned apertures in the cover plates and body.

A rotatable operating shaft 10 of insulating material extends laterally of the housing, and has affixed thereto an operating lever 12. Movement of lever 12 rotates shaft 10 and in so doing, through elements that will be described hereinafter, the switching action takes place.

Referring now to the enlarged drawings, Figs. 4 to 8, it will be seen that there are two spaced terminals 14 and 16, having their inner ends fixed in position by being wrapped around supports 18 and 20. Surface inserts of appropriate contact material have been made at 22 and 24 for the purpose of lengthening the life of the switch.

An intermediate terminal 26 in the form of a flexible strip of beryllium copper, Phosphor bronze or other suitable material is mounted as shown. This strip has been given extra support by a heavy backing strip 28 along its exterior portion and along that portion secured to the housing. A two-sided contact 30 is mounted on strip 26, which contact is adapted to make alternate contacts with fixed contacts 22 and 24. Strip 26 may be referred to hereinafter as the contact lever.

Strip 26 has a normal set to the right, which, were it not for the other mechanisms, would normally hold contact 30 against contact 24, as shown in Figs. 5 and 6.

Around that part of shaft 10 which is within the body 6 is wrapped a strip of sheet material 32 rigid enough for the purpose intended and having one end 34 embedded in slot 36 that extends longitudinally in shaft 10. The other end of strip 32 is slit longitudinally for a short distance to divide the end into three narrower strips, one continuing around shaft 10 as at 38, the middle part doubled back to form a hook 40 which is adapted to receive and engage the end of the semicircular extension 42 of strip 26, and the third part extending upwardly away from shaft 10 as at 44 to act as a stop when it comes into engagement with a protuberance 46 extending downwardly from the interior of the body. The engagement of hook 40 with extension 42 occurs preferably over the width of the hook 40 as indicated in Fig. 7 and the contact between the two may be referred to as the area of engagement.

On the outer extension of shaft 10 is secured operating lever 12, long enough to provide the leverage required to operate the switch under the weight of a coin.

In Fig. 8 is shown the hair spring that overcomes not only the normal set of strip 26 but also the turning force caused by the mass of the unweighted lever 12. The hair spring thus holds the switch in the normal position shown in Fig. 4. The hair spring, numbered 48 in Fig. 8, has its inner end 50 bent at an angle and positioned in slot 36, while its outer portion 52 passes between two guide posts 54 and 56, with the end coiled about the end post 58. The hair spring is coiled so that it normally urges shaft 10, as viewed in Fig. 8, clockwise. Shaft 10 in Figs. 4, 5 and 6, being viewed from its opposite end, is urged counterclockwise by the hair spring. As previously mentioned, the torsional effect of the hair spring is sufficient

to overcome the resistance of strip 26 and the weight of lever arm 12 to cause the switch to assume as its normal position that shown in Fig. 4. Therefore, when shaft 10 is caused to rotate clockwise by a force being applied downwardly to lever arm 12, as viewed in Figs. 4, 5 and 6, the normal set of strip 26 assists lever arm 12 in overcoming the resistance of the hair spring. That is to say, hair spring 48 is adjusted to have just enough rotative force to overcome the resistance of strip 26, which is constantly pressing through the end of semicircular portion 42 against hook 40, and the unweighted mass of lever 12, which is continually exerting a clockwise force on shaft 10, as viewed in Figs. 4, 5 and 6.

It should be mentioned that shaft 10 is carried by two closely fitting bearings 60 and 62, the former being in side plate 2 and the latter 20 in the body 6. The accurate close fit of the bearings as shown in the drawing will have the usual and obvious effect of restricting and limiting the passage therethrough of extraneous matter of all kinds. If it is found desirable to have shaft 10 extend from the opposite side of the housing, this may be readily accomplished by merely reversing shaft 10 to have the extension that carries lever arm 12 carried by the bearing 64 in side plate 4 instead of by bearing 60. Without further explanation, it is believed obvious that shaft 10 is reversible, as the only structural feature in the shaft is the slot 36 into which the end 34 of strip 32 and end 50 of hair spring 48 may be inserted as readily with the shaft in one position or the other.

The effect of reversing the shaft in the housing so that the end to which the lever arm 12 is connected extends from cover plate 4 rather than from cover plate 2 is to reverse the direction in which arm 12 is rotated with respect to the housing in the switch operation. That is to say, lever arm 12 is to be rotated counterclockwise, as viewed in Fig. 1. If the shaft is reversed, then the arm rotation when viewed from the arm side of the housing will be clockwise. This construction makes it possible to provide for right or left hand operation in a single unit without need of extra or alternate parts.

The feature of the over-travel construction is illustrated in Figs. 4, 5 and 6. In Fig. 4, lever arm 12 is in normal position with contacts 22 and 30 in engagement. When a descending coin engages lever 12, the latter will immediately be swung downwardly to the position indicated in Fig. 5, at which point contact 30 has engaged contact 24 under the force of the strip spring 26. At this time the end of the semicircular extension 42 will be ready to free itself from engagement in the notch formed by hook end 40. Thus, as the weight of the coin carries lever 12 downwardly still further to a position as illustrated in Fig. 6, there will be no further movement of semicircular portion 42 or the contacts 30 and 24. In Fig. 6 it is noted that hook member 40 has moved away from the end of member 42 an angular amount equal to the angular movement of lever arm 12.

The dotted line position of lever arm 12 and hook 40 in Fig. 6 are merely included to show the possible extent of overtravel of lever arm 12 that could take place if conditions required it.

As soon as lever arm 12 has been freed of the weight of the operating coin, then hair spring 48 comes into play to rotate shaft 10 counterclockwise, as viewed in Figs. 4, 5 and 6. Hook

40 comes into engagement with the end of member 42 at the position shown in Fig. 5, and thereafter continued rotation of shaft 10 will break the engagement between contacts 24 and 30 and will bend strip 26 to the left so that contacts 30 and 22 again come into engagement, as in Fig. 4.

As shaft 10 rotates counterclockwise under the influence of the hair spring, its movement is checked or snubbed prior to the time that finger 44 comes into actual engagement with stop 46. This snubbing action is desirable for the reason that if it were not present finger 44, hitting stop 46 at considerable speed, would rebound therefrom one or more times and the switch would chatter.

The snubbing action is achieved by the mutual action of hook 40 and the end of member 42. Hook 40 pivots about the center of shaft 10 while the outer end of member 42 pivots in effect about a point below contact 30 and very close to that part of the housing that supports strip 26. Hook 40 acts as a fulcrum and engages the end of member 42 at about the position shown in Fig.

5. Thereafter, as hook 40 rotates to the left and is guided by its association with shaft 10, it follows a downward arc or trajectory that does not coincide with the normal arc of the end of member 40, and as a result the extreme end of member 42 is flattened, as indicated at 43 in Fig. 4, and acutely bent at 45, while the remainder of member 42 is bent generally into a smaller circle.

The resistance of member 42 to assuming its new shape causes upward pressure against the under side of hook 40, which in turn presses shaft 10 with increasing force against the bearing surfaces 60 and 62. This increasing friction slows down the rotation of shaft 10 under the influence of the hair spring, and brings the shaft to a complete halt before finger 44 engages stop 46. However, before shaft 10 has stopped its counterclockwise movement, contact 30 will be in engagement with contact 22.

By the construction thus described, it will be apparent that the load on lever arm 12 may be instantly removed without danger of the switch chattering on the rebound. The distorted end of member 42 which has checked counterclockwise rotation of shaft 10 assists in the initial clockwise movement the next time a downward force is applied to lever arm 12.

Fig. 7, which is a section on the line 7—7 of Fig. 5, illustrates the manner in which strip 26 has been reduced in width in order to provide for maximum sensitivity under the rotative influence of hair spring 48 in one direction and lever arm 12 in the other. While strip 26 is reduced in width, nevertheless, because of the material of which it is made, there is sufficient resiliency to insure that contact 30 will be held tightly against contact 24 after the two have come into engagement, there being no force of the hair spring to overcome, as that has been taken care of by lever arm 12.

In Figs. 9, 10 and 11 is shown a modified form of the invention which operates in substantially the same way as that disclosed in the other figures.

Referring to Fig. 9, it will be noted that both ends of the shaft 70 are supported by closely fitting bearings 72 and 74. The accurate fit of the bearings acts to limit and restrict the passage of extraneous matter into the housing. Square sections 76 and 78 are provided at each end of

the interior portion of the shaft. These square sections are designed to engage the flat side 80 of the inner end of the hair spring 81 shown in Fig. 11. The center part of shaft 70 comprises a cam 82 which acts with respect to the movable switch member in much the same manner as hook 40 shown in Figs. 4, 5 and 6. Cam 82 has its rotation limited in either direction by engagement with the bottom surface 84 of the opening 86 through the central housing 85. The shaft 70 and cam 82 are made of insulating material.

The fixed contacts in Figs. 9, 10 and 11 are numbered 88 and 90, and the movable contact 92. This latter is supported by a flexible spring strip 94 carried by a reinforcing member 96 and mounted in the housing 85. The upper end 98 of strip 94 is located to be engaged over its width by a wiping action of cam 82. The contact between the strip and cam may be referred to as the area of engagement. When shaft 70 is rotated clockwise from the position shown in Fig. 9, cam 82 will slide upwardly along the right hand surface of member 98 with the area of engagement moving upwardly until contact 92 has moved to the right to engage contact 90. This occurs because hair spring 81 is being overcome by the rotation of shaft 70, and strip 94, being biased to the right, moves contact 92 to a position against contact 90 as cam 82 retreats clockwise. Thereafter, cam 82 may overtravel clockwise until it engages surface 84 without causing any further movement whatsoever of contacts 92 and 90.

When the clockwise rotative force is removed from the controlling lever, hair spring 81 will cause shaft 70 to rotate rapidly counterclockwise. In order to prevent chattering of the switch, cam 82 provides snubbing means which brings the rotation of shaft 70 to a standstill before or about the time member 98 has come into engagement with stop 100. This snubbing action is by virtue of the gradually increasing frictional engagement between the surface of cam 82 and the corresponding surface of member 98. It is believed obvious that the greater the extent of rotation of cam 82 counterclockwise after engagement with member 98, the greater will be the frictional force therebetween. The parts are so designed that when member 98 hits stop 100, the cam will be in a wedging position, which will preclude any opportunity of contact 98 jumping back off contact 88.

When initial force is applied to the lever arm 55 thereafter to cause clockwise rotation of shaft 70, there will be a somewhat greater force to overcome than would be the case in the construction shown in Figs. 4, 5, 6 and 7. This difference, however, is slight, and does not affect normal operation.

As will be noted in Fig. 10, reversal of the shaft may be accomplished by removal of the two covers 99 and 101, breaking away the knockout section 102, removing the hair spring from the squared end 78, and then reversing the shaft, applying the hair spring to squared end 76, and replacing the covers so that the long end of shaft 70 rests in bearing 74, while the short end rests in bearing 72. The construction of Figs. 9, 10 and 11 differs from Figs. 4, 5, 6 and 7 in that in the former the shaft is supported by bearings in the two covers rather than by a bearing in one cover and another bearing in the main body of the housing. In initial assembly, one cover will be left with a

knockout section indicated at 102 in both Figs. 7 and 10.

It should also be observed that the central portion of the housing 85, as shown in Fig. 10, is symmetrical, so that if desired the movable contact 92 and all associated parts may be reversed along with the cam and the hair spring. Thus, with the parts reversed, counterclockwise rotation of shaft 70, as viewed in Fig. 9, will enable contact 92 to move under the influence of strip 94 to the left against contact 88, while clockwise movement of the shaft will bring cam 82 against member 98, which will then be to the right of shaft 70. This will move contact 92 away from contact 88 to engage contact 90.

Extension 42 of the contact lever or strip 26, as shown in Figs. 4-8, is generally circular in form, while the upper end 98 of strip or contact lever 94 is in the form of a very flat L. Nevertheless, it will be understood that the particular configuration of the extension of the contact lever may be varied without departing from the invention, so long as it is adapted to be engaged by the particular operating means on the crank shaft. Thus, in Figs. 4-7 the hook 40 is suitable for engaging the end of extension 42 to produce a lateral movement and a downwardly compressive cam-like effect which bends the extension, as illustrated in Fig. 4. The crank shaft 70, carrying cam 82, is likewise effective to move the extending member 98 laterally and at the same time have a wiping cam-like effect to check rotation.

The extensions 42 and 98 are both in the form of leaf springs, and are subject to greater or less bending, depending upon the extent of the rotation of the crank shaft. In general, it may be said that that portion of the contact lever in the lower section close to the point of support by the housing is of more limited flexibility than the outer portion beyond the contact which is acted upon by the cam mechanism.

It should also be pointed out that the commercial form taken by the switch of the present invention is of relatively small size, and is often referred to in the trade as a "midget-type" switch. However, the fact that in practice the parts will normally be small is not to limit the scope of the invention to small switches. On the contrary, the various parts may be enlarged to whatever size is deemed necessary for particular service requirements.

In the midget type form of the switch, the actual volume of air therein will be very small, as the housing has been designed to closely encompass the various working parts. Since the fit of the shaft in the bearings as shown in the drawings is close and the housing itself is otherwise sealed, it is apparent that the humidity of the atmosphere within the housing will change slowly, if at all, as outside conditions may vary.

In the small cavity of the housing, the amount of moisture in suspension in the air therein obviously would form, if condensed, only a minute quantity of water. Additional outside more humid air would have difficulty entering the housing due to the close fit between the shaft and bearings as shown in the drawings. Thus, the limitation of condensate within the housing minimizes the possibility of malfunctioning of the switch.

The foregoing description shows that I have provided a switch effective to operate under small force applied to the lever arm and on release to be free from chattering. Further-

more, the switch is reversible, so that it may meet more manufacturing requirements than would otherwise be the case. While preferred forms of the invention have been disclosed, it is not intended that the invention shall be limited thereby but only by the appended claims.

I claim:

1. In a switch of the type described, a housing comprising a central body portion and opposed cover plates, two axially aligned bearings carried by said plates, a shaft mounted for rotation in said bearings, a coiled spring for urging the rotation of said shaft in one direction, cooperating stop means for limiting rotation of said shaft by said coiled spring, a second spring applying a force substantially tangentially of said shaft in a direction opposed to that of said coiled spring, and a lever arm connected to said shaft whereby a force may be applied to said lever arm to assist in rotating said shaft in a direction opposite to that being urged by said coiled spring, and a pair of contacts within said housing adapted to be opened or closed by rotation of said shaft in one direction or the other.
2. In a switch of the type described, a housing comprising a central body portion and oppositely disposed cover plates, two axially aligned bearings carried by said plates, the connection between said body portion and cover plates being tight, a shaft of insulating material mounted for rotation in said bearings, the fit between said shaft and bearings being close while allowing free rotation of said shaft, a hair spring surrounding said shaft and connected to said shaft and housing for urging rotation of said shaft in one direction, a flexible strip mounted within said body portion and curving partially around said shaft, a contact on said flexible strip, a second contact mounted on said housing at a position where it may be engaged by the said first contact, said flexible strip having a permanent bias in that part between said second contact and said housing whereby said contacts would normally be in engagement unless held apart, a cam on said shaft for engaging said flexible strip above said second contact whereby when said shaft and cam are rotated under the influence of said hair spring, the end of said flexible strip will be moved to a position against a stop on said housing and said cam will cause increased concave bending of that part of said strip above said second contact to maintain said contacts separated and incapable of engagement until said shaft and cam are rotated through a substantial angle in the opposite direction, and a lever attached to said shaft exterior of said housing to provide means whereby said shaft may be rotated in said opposite direction through a substantial angle upon the application of a small force to said lever.
3. In a switch of the type described in combination, a contact lever, a support for said lever permitting angular reciprocatory movement thereof, a curved leaf spring forming an extension of said lever arranged at an angle to said lever, a stationary contact for engaging said lever at a point situated between said support and said curved leaf spring, said contact forming an abutment limiting the closing stroke of said lever, said lever being biased so as to cause separation of said lever from said contact if said lever is unopposed, a rotatable operating member for actuating said contact lever into engagement with said contact against said bias, said

operating member comprising a relatively long arm adapted to be acted upon by an external force and a relatively short arm, said short arm being adapted to transmit to said extension of said lever during the closing stroke thereof an operating force at a changing angle with respect to said contact lever, a second abutment for limiting the movement of said curved leaf spring and the closing stroke of said operating member, said stationary contact and said second abutment being arranged to cause sequential stopping of the corresponding engaged parts of said contact lever to permit overtravel of said operating member and subsequent back bouncing of said operating member without disengagement of said contact lever from said stationary contact.

4. In a midget type switch, the combination of a biased contact lever, fulcrum means for said lever permitting angular reciprocatory movement thereof, a first stationary contact arranged on one side of said lever and adapted to cooperate therewith, a second stationary contact arranged on the other side of said lever and adapted to cooperate therewith, said biased contact lever tending to move into engagement with said first contact, said lever having an extension in the form of a curved leaf spring and forming an integral part thereof, a force applying member for engaging the said extended leaf spring, means for moving said member to force said lever into engagement with said second contact and thereafter to cause additional bending of said leaf spring between said second contact and the end of said leaf spring, said bending producing increasing concavity of said curved leaf spring, said moving means including a shaft for rotating said member and located alongside of said curved leaf spring and in alignment with said contact lever and a second biasing means acting upon said shaft and capable of overcoming the bias of said contact lever, and lever means acting upon said shaft for counteracting the bias of said second biasing means upon the application of a small force to said lever to permit said biased contact lever to move into engagement with said first stationary contact.

5. In a midget type switch, the combination of a leaf spring contact lever, means for clamping one end thereof, a first stationary contact limiting the stroke of said lever in one direction, a second stationary contact limiting the stroke of said lever in the opposite direction, said lever being biased toward said first contact, a substantially curved leaf spring, one end thereof arranged in angular relation with respect to said lever and forming an integral part thereof, a cam acting on the said leaf spring, means for moving said cam to cause engagement of said lever with said second contact and to deflect said leaf spring, said moving means including a crank shaft and spring means acting upon said crank shaft and capable of overcoming the bias of said lever, and lever means associated with said crank shaft for counteracting said spring means to permit said contact lever to engage said first contact.

6. A non-chattering switch of the type described comprising a fixed immovable contact, a movable contact lever with a complementary contact thereon and biased away from said fixed contact, a flexible extension on the end of said contact lever set at an angle thereto, a rotatable shaft with a laterally extending member thereon, said member adapted when rotated in one

5 direction first to engage said extension at a constantly changing angle and as rotation continues to move said extension and contact lever until said complementary contact is moved into engagement with said fixed contact, a coil spring of such strength as to not only cause the rotation of said shaft and member and the closing of said contacts as aforesaid but also to cause further rotation of said shaft and member and flexing of said extension under the pressure of said member after engagement of said contacts, whereby said contacts cannot be opened until said shaft has been rotated somewhat in the reverse direction, and a lever of such length 10 on said shaft that the application thereto of a small force in the order of the weight of a coin will be sufficient to overcome said coil spring to rotate said shaft in the opposite direction to permit the bias of said contact lever to cause separation of said contacts.

7. In a midget type switch, the combination of a first stationary contact, a second stationary contact, a leaf spring contact means adapted to cooperate with said contacts, a support for said leaf spring contact means permitting angular reciprocatory movement thereof, said leaf spring contact means comprising a first portion substantially straight and a second portion extending in curved formation from said first portion, said first portion being adapted to engage selectively either of said stationary contacts and being biased to engage said first stationary contact, means for overcoming the bias of said first portion toward said first stationary contact and for actuating said first portion into engagement with said second contact, said means comprising a rotatable shaft arranged on the concave side of said second portion and in alignment with said first portion, a force applying member on said shaft for engaging said second portion remote from said support, and spring means sufficiently strong to rotate said shaft and member to overcome the bias of said first portion and to bring said leaf spring contact means into engagement with said second contact and then to increase the concavity of said curved second portion whereby said shaft must be rotated somewhat in the reverse direction before said leaf spring contact means and said second contact can be separated, and lever means associated with said shaft for counteracting said spring means and causing rotation of said shaft and member by the application of a small force to said lever to remove the force of said member from said second portion and to permit the bias of said first portion to cause engagement thereof with said first stationary contact.

8. In a midget type switch the combination of a leaf spring contact lever, means for clamping one end thereof, a first stationary contact limiting the stroke of said lever in one direction, a second stationary contact limiting the stroke of said lever in the opposite direction, said lever being biased toward said first contact, a substantially curved leaf spring, one end thereof arranged in angular relation with respect to said lever and forming an integral part thereof, a shaft having a lateral extension for engaging said leaf spring when said shaft is rotated, means for rotating said shaft to cause said extension to engage and deflect said leaf spring thereby to cause said lever to engage said second contact and thereafter to cause additional bending of said leaf spring upon further rotation of said shaft, said means for rotating said shaft in-

cluding spring means acting upon said shaft and capable of overcoming the bias of said lever, and a lever associated with said shaft providing means for applying rotative force to said shaft in the opposite direction to counteract said spring means to permit said contact lever to engage said first contact.

9. In an electric switch, in combination, a stationary contact, a movable contact cooperating therewith, a leaf spring carrying said movable contact and acting as means tending to cause separation of said movable contact from said stationary contact, said leaf spring having a substantially straight portion and a curved portion, a fixed support for said straight portion permitting angular reciprocatory movement of the said straight portion, a movable member for engaging said curved portion, guiding means for said movable member to cause movement thereof along a trajectory such that the area of engagement of said movable member with said curved portion progressively decreases in distance from said stationary contact and from said fixed support for causing engagement of said movable contact with said stationary contact and for stressing the curved portion of said leaf spring when the area of engagement of said movable member with said curved portion is moved further along said trajectory, and operating means for moving the said area of engagement of said movable member along said trajectory.

10. In an electric switch, the combination of a stationary contact, a movable contact adapted to cooperate therewith, means tending to cause separation of said movable contact from said stationary contact, said means comprising a leaf spring carrying said movable contact and having a curved portion, a fixed support for said leaf spring permitting angular reciprocatory movement of that portion carrying said movable contact, a movable member for engaging said curved portion, a rotatable shaft for supporting said movable member in spaced relation to the geometrical axis of said shaft, said movable member being arranged to move in a plane at right angles to the geometrical axis of said shaft, and operating means for rotating said shaft and movable member to cause engagement of said movable contact with said stationary contact, the said

curved portion of said leaf spring being sufficiently flexible to permit limited continued rotation of said shaft upon engagement of said stationary contact by said movable contact which 5 continued rotation is accomplished by additional bending of said curved portion to increase the concavity thereof.

11. In a switch of the type described, the combination of a stationary contact, a switch lever 10 cooperating therewith, a fixed support for said switch lever permitting angular reciprocatory movement thereof, resilient means on said switch lever remote from said fixed support, a movable member for applying a force to said resilient 15 means, a rotatable shaft supporting said movable member in spaced relation to the geometrical axis of said shaft, said switch lever having a bias tending to cause separation of said switch lever from said stationary contact, spring means 20 for rotating said shaft and said movable member to cause said switch lever to engage said stationary contact, said movable member being adapted to be moved by further rotation of said shaft after engagement of said switch lever and said stationary contact from a position wherein the stress 25 of said resilient means and the bias thereof in a direction inwardly radially of said shaft are relatively small toward a position wherein the stress of said resilient means and the bias thereof in a direction inwardly radially of said shaft are 30 relatively large.
